(57) **CLAIM**

The ornamental design for a grate for gas oven range, as shown and described.

DESCRIPTION

1. Grate for gas oven range
  - 1.1 is a top, front, and right side perspective view of a grate for gas oven range showing our new design;
  - 1.2 is a front elevation view thereof;
  - 1.3 is a rear elevation view thereof;
  - 1.4 is a left side elevation view thereof;
  - 1.5 is a right side elevation view thereof;
  - 1.6 is a top plan view thereof;
  - 1.7 is a bottom plan view thereof; and
  - 1.8 is a top, front, and right side perspective view thereof as mounted on top of an exemplary gas oven range.
- The broken line showing of the gas oven range is provided for the purpose of illustrating environmental structure and forms no part of the claimed design.
